CLAIM

[21] Appl. No.: 67,810

The ornamental design for a grippable monitor support, as
shown and described.

[22] Filed: Mar. 14, 1997

DESCRIPTION

[51] LOC (6) Cl. 14-02

FIG. 1 is a front view of a grippable monitor support
constructed in accordance with a preferred embodiment of
the invention, the monitor support being shown in a stowed
orientation with a monitor indicated by dashed lines for
illustrative purposes only;

[52] U.S. Cl. D14/114; D8/349

FIG. 2 is a left side view of the grippable monitor support
shown in FIG. 1;

[58] Field of Search D14/100-114;

FIG. 3 is a right side view thereof;

248/281.11, 278.1, 280.11, 917-920, 284.1,
285.1, 286.1; 361/680-686; D19/91; 348/837,
827; D8/354, 373, 349, 363

FIG. 4 is a top view thereof;

[56] References Cited

FIG. 5 is a bottom view thereof; and,

U.S. PATENT DOCUMENTS

FIG. 6 is an isometric view of the grippable monitor support
shown in FIG. 1, but with the monitor support in a display
orientation.
